UNITED STATES PATENT OFFICE.

JOSEPH H. KLEPPINGER AND JAMES N. NAYLOR, OF CHERRYVILLE, PA.

MACHINE FOR MEASURING CLOTH.

SPECIFICATION forming part of Letters Patent No. 267,901, dated November 21, 1882.

Application filed March 31, 1882. (Model.)

To all whom it may concern:

Be it known that we, JOSEPH H. KLEPPINGER and JAMES N. NAYLOR, of Cherryville, in the county of Northampton, and in the State of Pennsylvania, have invented certain new and useful Improvements in Machines for Measuring Cloth; and we do hereby declare that the following is a full, clear, and exact description thereof, reference being had to the accompanying drawings, and to the letters of reference marked thereon, making a part of this specification.

This invention has for its object to provide an improved machine for measuring cloth and winding upon the boards commonly employed for convenience in handling, and it is specially designed to furnish a convenient means whereby retail dealers may arrange and measure their materials as they come from the factory, and facilitate the taking account of stock, as more fully hereinafter specified. These objects we accomplish by the means illustrated in the accompanying drawings, in which—

Figure 1 represents a side elevation of our improved apparatus; Fig. 2, a front view thereof, and Fig. 3 a vertical sectional view of the same.

The letter A designates a frame constructed of suitable material, and provided at one side with a rotary shaft, B, having a crank, C, at one end and a chuck, D, at the other. The opposite side of the frame is provided with an adjustable rod, E, which is for the purpose of adapting the machine to be used with winding-boards of different lengths, and is provided with a rotating chuck, F, having a recess, G, at its end, the two chucks being adapted to clamp the ends of the board H, upon which the cloth is to be wound.

The letter I indicates a supplementary frame, secured to the frame A by means of the screw-bolts M and thumb-nuts N, the bolts being provided with sleeves P, in order to set the nuts out in convenient position to be operated to fasten the supplementary frame to the main frame. The supplementary frame is provided with a longitudinal slot, R, and a roller, S, and also with a slotted tension-bar, T, which has an adjustable guide, U, at one side for the purpose of keeping the cloth straight, as more

fully hereinafter specified. The bar T is pivoted at its ends to the supplementary frame, so that it may be partially turned or adjusted to regulate the tension of the cloth. The roller S has secured to one end of its shaft a pinion, V, which intergears with a cog-wheel, W, journaled on a stud or pin, Y, secured to the frame A. The said cog-wheel has on its outer face a projection, Z, which is adapted to operate in conjunction with the teeth of a cog-wheel, A', 55 suitably journaled to the frame A and provided with a graduated disk, B', on its face to indicate the length of cloth wound upon the board, an index or pointer, C', being secured to the frame A, to keep the record as the disk 60 B' rotates.

The operation of our invention will be evident from the above description, and is as follows: One end of the cloth to be measured and baled is secured to the flat board, which 70 is clamped between the chucks above mentioned, the cloth extending through the longitudinal slot of the supplementary frame over the roller and through the slot in the tension-bar, its passage through the same being regulated by the guide-screw and thumb-nut, so as 75 to deliver it properly to the bale-board.

Having thus described our invention, what we claim, and desire to secure by Letters Patent, is—

The supplementary frame I, having longitudinal slot R, roller S, pivoted slotted tension-bar T, with adjustable guide U, and secured to main frame by bolts M having sleeves P and thumb-nuts N, the pinion V, cog-wheel W, 85 having projection Z, stud Y, cog-wheel A', graduated disk B', and pointer C', in combination with the frame A, provided with shaft B, crank C, chucks D and G, and adjustable shaft E, as described, and for the purposes set 90 forth.

In testimony whereof we affix our signatures, in presence of two witnesses, this 16th day of March, 1882.

JOSEPH H. KLEPPINGER.
JAMES N. NAYLOR.

Witnesses:

JOHN M. HOWER,
A. W. MUNMEY.
